UNITED STATES PATENT OFFICE.

ROBERT P. WALKER, OF CLEVELAND, OHIO, ASSIGNOR TO NATIONAL CARBON COMPANY, OF CLEVELAND, OHIO, A CORPORATION OF NEW JERSEY.

ARC-LIGHT ELECTRODE.

1,225,194.

Specification of Letters Patent.

Patented May 8, 1917.

Application filed December 3, 1912. Serial No. 734,656.

To all whom it may concern:

Be it known that I, ROBERT P. WALKER, a citizen of the United States, residing at Cleveland, in the county of Cuyahoga and State of Ohio, have invented a certain new and useful Improvement in Arc-Light Electrodes, of which the following is a full, clear, and exact description.

My invention relates to a novel way of arranging the end of the conducting wire in cored carbons.

Cored carbons have a relatively high resistance and to overcome this objection it is the common practice to extend a brass, zinc or other metal wire throughout the length of the carbon. Such a low resistance conductor is disclosed in Patents 982,407 and 1,000,717. In the former the wire is bent at right angles to lie across the end of the 20 core. In the latter the wire is flattened and bent down over the side of the electrode.

In making electrodes in accordance with these prior patents the wire was first inserted in the channel, clipped off and bent 25 across the core or flattened and bent down the side of the electrode. The core composition was afterward forced into the core opening. On account of the bent end of the wire being in the way, the composition was 30 forced in from the other end of the electrode. The material, however, sometimes forced the wire outward when admitted from the arc end of the electrode. The bent end also furnishes too little surface contact as it is necessarily 35 short. In addition it is difficult to electroplate and solder the wire to the core. When the wire was flattened it often broke and destroyed the continuity of the circuit. My improvement overcomes these objection- 40 able features in a manner set forth in the following description.

In the drawings:

Figure 1 is an end view of an electrode with my improvement.

Fig. 2 is a sectional view of the electrode end taken on the line A—A of Fig. 1.

The electrode has a carbonaceous shell 1 and a central hole 2 extending throughout its entire length. A small channel 3 runs 50 parallel to the hole 2 and communicates

therewith through a slot 4. In some forms of electrodes the channel 3 does not open into the central hole. The wire 5 has one end bent in the form of a ring 6. This ring is preferably of larger diameter than the 55 hole 2 so that the core composition 7 can be forced into or out of the hole without meeting any interference from the ring. After the wire is put in place the composition is forced into the hole from either end of the 60 electrode. It also enters the channel 3 through the slot 4 and envelops the wire 5. Afterward the core 7 is compressed by pressing a small rod through the ring 6 leaving usually a space at the holder end 65 as shown, though this may be dispensed with if desired. However, it has been found advantageous to compress the composition in this way and the ring permits of this being 70 readily done.

The electrode is afterward heated to dry the core and the holder end is electroplated and dipped in solder to integrally unite the ring to the carbon shell. The electroplate and solder is shown at 8.

When the wire is bent around to lie on the end of the shell the area of contact is greatly increased between the ring and coat of solder. The current can therefore flow from the holder through the solder and wire without undue generation of heat. The ring itself in abutting against the bottom of the holder also furnished an increase in contact 80 surface therebetween.

Having described my invention what I 85 claim is:

An arc lamp electrode having two longitudinal channels, flaming material in one of said channels and a metallic conductor in the other channel, the protruding end of said 90 conductor being looped around the core of flaming material and secured to the electrode end.

In testimony whereof, I hereunto affix my signature.

ROBERT P. WALKER.
